Primary Examiner — John A Voytek

(57) **CLAIM**

The ornamental design for an aerial vehicle, as shown and described.

DESCRIPTION

FIG. 1 is a perspective view of an aerial vehicle in an expanded state showing our new design;

FIG. 2 is a perspective view viewed from another angle thereof;

FIG. 3 is a front elevation view thereof;

FIG. 4 is a rear perspective view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area "9" shown in FIG. 1;

FIG. 10 is an enlarged view of the area "10" shown in FIG. 1;

FIG. 11 is an enlarged view of the area "11" shown in FIG. 1;

FIG. 12 is an enlarged view of the area "12" shown in FIG. 1;

FIG. 13 is an enlarged view of the area "13" shown in FIG. 2;

FIG. 14 is a perspective view of the aerial vehicle in a folded state showing our new design;

FIG. 15 is a perspective view viewed from another angle thereof;

FIG. 16 is a front elevation view thereof;

FIG. 17 is a rear perspective view thereof;

FIG. 18 is a left side elevation view thereof;

FIG. 19 is a right side elevation view thereof;

FIG. 20 is a top plan view thereof; and,

FIG. 21 is a bottom plan view thereof.

The broken lines depict portions of the aerial vehicle in which the design is embodied that form no part of the claimed design.

1 Claim, 21 Drawing Sheets
